UNITED STATES PATENT OFFICE.

WILLIAM RUBIN, OF OMAHA, NEBRASKA.

DESIGN FOR A DIE.

SPECIFICATION forming part of Design No. 32,879, dated June 26, 1900.

Application filed May 26, 1900. Serial No. 18,162. Term of patent 14 years.

To all whom it may concern:

Be it known that I, WILLIAM RUBIN, a citizen of the United States, residing at Omaha, in the county of Douglas and State of Nebraska, have invented and produced a certain new and original Design for Dies, of which the following is a specification.

My invention resides in a design for a die, substantially as shown in the accompanying drawings, in which—

Figure 1 is a sectional elevation of a die made according to my design, and Fig. 2 is a view of the face thereof.

Like reference-numerals indicate like parts in both views.

The body 1 of the die is formed with a central circular aperture 2, and the active face of the die is formed with two concentric circular grooves or channels 3 and 4. Adjacent to the aperture 2 and surrounding the same is a projection 5, having a sharpened edge formed by the inclined wall 6. Adjacent to the groove or channel 3, but inside the same, is a similar projection 7, having a sharpened edge formed by the inclined wall 8 and the perpendicular wall 9. The projection 7 is, as shown, slightly higher than the projection 5. The inclined wall 8 forms one side of an annular recess just outside the aperture 2, the other side thereof being formed by the inclined wall 10. Just outside the recess, but concentric therewith, is another annular recess formed by the inclined walls 11 and

12, the latter recess lying just within the circular projection 7, heretofore referred to. 35

The outer wall of the groove or channel 3 forms, with the inclined wall 13, a circular projection 14, slightly lower than the projection 7. Outside the projection 14 is a circular groove or depression, one side of which is formed by the wall 13 and the other side by the inclined wall 15. Surrounding this latter recess is an annular recess or depression formed by the inclined walls 16 and 17. Adjacent to the inclined wall 17 is a perpendicular wall 18, extending outwardly and forming, with the inclined wall 19, a circular projection 20, having a flat face and slightly higher than the projections 14 and 7, heretofore referred to. The face of the die outside the groove or channel 4 is flat, as shown at 21, forming a sharp corner 22. From the flat portion 21 the die is cut away to form the inclined wall 23, adjacent to which are the walls 24 and 25, perpendicular to each other. 50 55

What I claim as my invention is—

The design for a die, substantially as shown and described.

In testimony whereof I have hereunto set my hand in presence of two subscribing witnesses.

WILLIAM RUBIN.
